INVENTOR

ATTORNEY

UNITED STATES PATENT OFFICE.

FREDERICK L. ALLEN, OF BOISE, IDAHO.

WRENCH.

1,409,811.

Specification of Letters Patent. Patented Mar. 14, 1922.

Application filed April 19, 1921 Serial No. 462,640.

To all whom it may concern:

Be it known that I, FREDERICK L. ALLEN, a citizen of the United States, residing at Boise in the county of Ada and State of

5 Idaho, have invented new and useful Improvements in Wrenches, of which the following is a specification.

This invention relates to wrenches, particularly to those of the class commonly 10 known as Stillson wrenches, and has for its object the provision of a wrench of this type embodying various advantageous features in point of construction, combination and arrangement of parts.

15 An important object is the provision of a wrench of this character which is provided with spring means for frictionally engaging an operating nut so that the nut may not be moved too easily.

20 An additional object is the provision of a wrench of this character which will be simple and inexpensive in manufacture, highly efficient in use, durable in service and a general improvement in the art.

25 With the above and other objects and advantages in view, the invention consists in the details of construction to be hereinafter more fully described, and claimed, and illustrated in the accompanying drawings, in 30 which:

Figure 1 is a perspective view of the wrench.

Figure 2 is a longitudinal section therethrough.

35 Referring more particularly to the drawings the numeral 10 designates the handle of my wrench which has its outer edge enlarged as shown and the end rounded toward the horizontal wall of the enlargement 40 as indicated by the numeral 11, this rounded edge being formed with a series of relatively fine teeth 12. The numeral 13 designates a carriage which has one of its ends provided with a depending portion 14 formed with a

45 slot or opening 15 through which the handle 10 passes. The under face of the portion 11 of the handle has secured thereto a flat spring 15 and the said spring is adapted to bear against the wall provided by the pas-

50 sage or opening 15. The carriage 13 is provided with an additional longitudinally extending passage 16 through which passes the shank 17 of a movable jaw 18. The shank 17 has its opposite longitudinal edges formed 55 with threads 19 and the carriage is provided with a transverse opening 20 for the recep-

tion of a milled actuating nut 21 which has its bore formed with threads coacting with the threads on the shank of the movable jaw.

60 Arranged upon the upper face of the handle 10 to the rear of the carriage 13 is a second flat spring 22 which has its end arranged within the slot or passage 15 contacting with the upper wall thereof. The 65 springs 16 and 22 sustain the handle 10 longitudinally of the depending portion 14 of the carriage as will be readily understood.

The forward and lower face of the carriage is provided with a slot 25 which is 70 adapted to receive a centrally arranged lug 26 provided upon the end 11 of the handle, while passing through the walls provided by the slot 25 is a pivot member 27 which connects the headed end 11 of the handle with 75 the carriage. The portions 24 and 11 provide the stationary jaw for the wrench. It will be noted that by providing the stationary jaw with the two heads 24 and 11 respectively, that when an article is received between the movable jaw and the stationary jaw, a swinging of the handle in the direction of the arrow will cause a pipe or other article to be gripped, indicated by the numeral 28, to be tightly compressed against 80 the rounded edge 24 and the rounded end 11 of the jaw while the said jaw may be readily swung in a reverse direction to the arrow in order to obtain a tighter grip upon the pipe or other article or to provide a ratchet movement of the wrench upon the pipe.

85 It is preferable that the free end of the shank of the movable jaw be formed with a knurled or milled depressed portion 29 engageable by the thumb of an operator whereby the movable jaw may be swung into its initial position when it is desired to engage the wrench upon a pipe or other article to be turned.

90 I also prefer to make use of a leaf spring 100 30 which has one end secured within the interior of the carriage 13 and which has its other end bearing upon the actuating nut. It will be observed that the interior of the carriage is hollowed out for the proper accommodation of the spring.

95 From the foregoing description and a study of the drawings it will be apparent that I have thus provided an extremely simple and inexpensive wrench which will be 110 very highly efficient for turning objects, especially those which are round or otherwise

not easily handled by means of ordinary wrenches. It is likewise to be observed that the provision of the auxiliary spring which bears against the operating nut prevents any undue looseness in this nut which might result in casual displacement of the parts or loosening or tightening of the wrench when it is undesired.

While I have shown and described the preferred embodiment of the invention, it is of course to be readily understood that I reserve the right to make such changes in the form, construction and arrangement of parts as will not depart from the spirit of the invention nor the scope of the subjoined claims.

Having thus described my invention I claim:

1. In a wrench of the character described, a handle having one of its ends enlarged and the outer edge of said enlargement rounded, a carriage having a passage for the reception of the handle, the handle being provided with oppositely disposed springs which engage with both the upper and lower walls of the passage, the carriage having the upper portion provided with a second passage for the reception of the shank of a movable jaw, the opposite longitudinal edges of the said jaw being notched to provide teeth, the said carriage having a transverse opening which intersects the upper passage for the reception of an actuating nut which engages with the threads of the shank of the movable jaw, the outer face of the carriage having its lower portion rounded and being provided with a slot, the enlarged end of the handle having a lug disposed within the slot and which is pivotally connected to the carriage, the said rounded lower portion of the carriage and the enlarged outer end of the handle constituting a stationary jaw for the wrench, the interior of the said carriage being partially hollowed out, and a leaf spring secured within said hollowed out portion and having its free end bearing against said actuating nut whereby to frictionally hold the same and prevent unduly free movement of the wrench thereof.

In testimony whereof I affix my signature.

FREDERICK L. ALLEN.

and the said rounded lower portion of the carriage and the enlarged outer end of the handle constituting a stationary jaw for the wrench.

2. In a wrench of the character described, a handle having one of its ends enlarged and the outer edge of said enlargement rounded, a carriage having a passage for the reception of the handle, the handle being provided with oppositely disposed springs which engage with both the upper and lower walls of the passage, the carriage having the upper portion provided with a second passage for the reception of the shank of a movable jaw, the opposite longitudinal edges of the said jaw being notched to provide teeth, the said carriage having a transverse opening which intersects the upper passage for the reception of an actuating nut which engages with the threads of the shank of the movable jaw, the outer face of the carriage having its lower portion rounded and being provided with a slot, the enlarged end of the handle having a lug disposed within the slot and which is pivotally connected to the carriage, the said rounded lower portion of the carriage and the enlarged outer end of the handle constituting a stationary jaw for the wrench, the interior of the said carriage being partially hollowed out, and a leaf spring secured within said hollowed out portion and having its free end bearing against said actuating nut whereby to frictionally hold the same and prevent unduly free movement of the wrench thereof.
